UNITED STATES PATENT OFFICE.

AXEL ANDERSON, OF CLIFTON, NEW JERSEY.

SHEARING IMPLEMENT.

1,218,157.

Specification of Letters Patent.

Patented Mar. 6, 1917.

Application filed April 18, 1916. Serial No. 92,013.

To all whom it may concern:

Be it known that I, AXEL ANDERSON, a citizen of Sweden, and resident of the town of Clifton, in the county of Bergen and State of New Jersey, have invented certain new and useful Improvements in Shearing Implements, of which the following is a specification.

This invention relates to shearing devices in which the cutting edges of a pair of blades are made to cross each other, as for example in scissors or the like, and it appertains more especially to implements employed for slitting, trimming or parting metal sheets or plates.

One of the objects of the invention is to produce an improved shearing instrument of the nature set forth, wherein the cutting elements are given a combined straight and sliding action calculated readily to clip the material operated upon, with the minimum expenditure of power.

A further object is the production of a shearing tool of the character described, including actuating members and cutting elements pivotally interconnected in such a manner as to afford a differential leverage serving to increase the purchase of the power utilized.

Another object is to provide a shearing appliance of the species mentioned capable of cutting around corners and sharp curves.

Still another object is the provision of a shearing contrivance of the type specified embodying means for predeterminedly varying the range of travel of the cutting elements.

A still further object is to devise a shearing instrument of the kind referred to, which shall be composed of few, simple and durable parts, convenient to manipulate and amenable to low cost of manufacture.

An additional object is so to mount and pivot the said actuating members and cutting elements one upon another, as to obtain concurrent movements of the shearing edges in opposite directions, without having recourse to shifting joints.

Other objects and advantages of the invention will become apparent as the specification proceeds.

With the aforesaid objects in view, the invention consists of the improvements, novel construction, arrangements and combinations of parts hereinafter described, defined in the subjoined claims, and illustrated

in their preferred embodiments by the annexed drawings, wherein like elements are designated by the same reference characters throughout.

In said drawings:

Figure 1 is a side view of the improved shears, in open position;

Fig. 2 is an end view thereof, as seen from the left hand side of Fig. 1, the rearwardly located handle parts being omitted;

Fig. 3 is a transverse section on the line 3—3 of Fig. 1, looking toward the left, in the direction pointed out by the arrows; and

Fig. 4 shows the reverse side of the shears, inverted as compared with Fig. 1, and in closed position.

In these several views the numerals 11 and 12 denote the handles or actuating members of the shears. These members are located side by side, preferably in the same plane as shown, and though respectively adapted to be moved toward or away from each other, they do not cross as is commonly the case with other implements appertaining to this class of invention.

A pair of blades or cutting elements 13, 14 is flexibly connected with the said actuating members, in such a way that a differential movement is effected therebetween, wherever there occurs a displacement or change of position of either one or both of the members. As represented in Figs. 1 and 4, the blade 13 is substantially L-shaped and has its cutting edge along the upper or inner margin of its base or jaw member 13^a. The blade 14 on the other hand, is shown as approximately straight, with the cutting edge at its free end. The edges of these blades, it will be noted normally meet at their inner corners and are designed to cross each other by degrees in opening and closing, as clearly indicated in the figures last named.

Preferably the cutting element 13 is connected by two pivot screws 15, 16 to the actuating members 11, 12 respectively. In a similar manner, screws or bolts 17, 18 pivotally connect the cutting element to both the said members. The arrangement is such that the distance between the pivots 15 and 17 which respectively couple the two cutting elements with the actuating member 11, is greater than that separating the pivots 16 and 18, which join the said elements to the actuating member 12. Besides, the pivots 15 and 16 connecting the element 13 with

the two actuating members 11, 12 are farther apart from each other than the pivots 17 and 18, that connect the element 14 with the said actuating members, are spaced between themselves. Moreover, the relative distances between the pivots 15—17 and 15—16 exceed the spacing between the pivots 16—18 and 17—18 by an increment equal in amount to the interval by which the pivots 16 and 18 are separated. Actual reduction to practice of this improved shearing device has borne out the theory that by following substantially the above outlined proportional arrangement of parts, which produces an interrelatively differential disposition of the pivotal connections between the actuating members and the cutting elements it will invariably yield the greatest obtainable purchase for the amount of energy expended.

As indicated in Fig. 1, the cutting elements are so placed relatively to each other as to form normally between them a pair of shearing jaws, with the element 14 lapping over the element 13, as at 14^a, when in an open position. The inner L-shaped element 13 has its jaw portion 13^a located outside of the actuating member 12, and therefore the latter is enabled always to clear the edge of a sheet or plate that is being cut, so that a very much sharper turn or curve can be effected or followed with this shearing implement than by using the ordinary type of snippers or shears, the handles of which stand at equal distances on both sides of the cutting edges. Due to the offset of the jaw 13^a externally of the pair of actuating handles, the operator of the shears can quickly cut around corners, which he could not reach nearly as well with similar tools not possessed of this feature.

Spacers 21, 22, conveniently in the nature of washers of same thickness as the inner blade 13, are interposed between the outer blade 14 and the pair of handles 11 and 12 around the pivots 17 and 18, respectively. These washers are used in order to bring the cutting edges of the two elements 13 and 14 into closer relation.

To afford adequate bearing surfaces for guiding the several pivot screws and the thereto related portions of the actuating members, links 23, 24 are provided on the side of the latter opposite from that where the cutting elements are located. The ends of these links are placed under the heads of the pivot screws, which in the present exemplification of the invention are shown as being of the button-head type. On the other side of the shears, the threaded end of the pivot screws are engaged by nuts and underlying washers, which maintain the cutting elements in proper relation to the actuating members. As shown, the link 23 is placed opposite the element 13 and takes over the pivots 15 and 16, while the link 24 engages

the pivots 17 and 18 and corresponds in position with the element 14.

Supplementary links 25, 26 are placed over the cutting ends of the pair of blades, one (25) extending between the screws 16 and 18, and the other (26) reaching from the screw 16 to another, somewhat smaller screw 27, passing through the handle 12. The latter named screw is sufficiently remote from the pivot 16 to afford free play to the blade 13 in all positions thereof, the link 26 serving as a guide for the same.

To the fastening screw 27, above mentioned is hinged a latch 30, on the other side of the handle 12 from that where the link 26 is positioned. This latch has a hook 31, adapted to take over the outer edge of the handle 11, and therefore available for the purpose of holding the pair of handles, together with the cutting elements, in closed position, as represented in Fig. 4.

A lever 32, having a cam portion 33, is hinged on the pivot screw 16, between the before mentioned links 25 and 26. As illustrated in Fig. 1, the minor axis of the cam 33 contacts with the near side of the cutting element 14, in which position it leaves entire freedom of motion to the element for its full working stroke. From this position the lever 32, which preferably is of resilient metal 95 and has a small protuberance 34 on its underside, can be pried up and swung outward so that the said protuberance will drop into engagement when released, either with a correspondingly shaped opening or socket 35 in the link 26, or with the outer edge of the latter. In the meantime the cam portion 33 is swung over to a proportional extent into the path of the blade 14, and operates to limit the return or opening movement thereof relatively to the blade 13.

A spring 40 is partially coiled around a pin or screw 41, which straddles the space between the cutting element 14 and the adjacent link 24. The terminals 42, 43 of this spring are located so as to bear respectively against the spacer 22 and the inner edge of the actuating member 11, and accordingly serving to open the jaws of the shears automatically after each cutting operation.

Grips 45 and 46 are attached to the ends of the actuating members 11 and 12 respectively, for convenience in operating the device.

While certain preferred embodiments of this device have been shown and described, it will be understood that changes in the form, arrangements, sizes, proportions and details thereof may be made, without departing from the scope of the invention as defined 120 by the appended claims.

Having described my invention what I desire to secure by Letters Patent and claim is:—

1. A shearing implement comprising actu- 130

- ating members adapted to be moved toward or away from each other, a cutting element disposed transversely at or near one end of said members with its cutting edge projecting laterally therefrom, a second cutting element similarly transverse to the members and located inwardly thereon with relation to the first mentioned element, said second element having an edge extending beyond 5 said first named edge so as to coat therewith, and pivotal connections separately joining the elements with each one of the members, said connections permitting one of the elements to move faster than the other.
- 10 15 2. A shearing implement comprising actuating members movable toward or away from each other, cutting elements with coacting edges offset laterally from said members, and a quadruple pivotal connection 20 joining the members with said elements, the pivots in said connection being spaced at progressive distances apart, commencing at a point adjacent to said edges and thence extending in a closed cycle from element to 25 element and member to member.
3. A shearing implement comprising actuating members operable toward or away from each other, a pair of cutting elements disposed transversely of said members with 30 converging edges at one side thereof, and a four-pivot connection between the members and said elements joining the same at unequal distances apart, the arrangement being such that the pivots spacing one element 35 with regard to the members and the other element are closer together than the pivots spacing the same members and said other element from the first mentioned element, whereby a differential shearing action is 40 produced between the pair of elements.
4. A shearing implement comprising separated actuating members movable laterally toward or away from each other, transversely disposed cutting elements on said 45 members, said elements having convergent edges differently offset to one side of the latter, and pivots joining the elements to the members independently one of the other, the pivots for the element having the outer edge being spaced farther apart than the pivots 50 for the element having the inner edge.
5. A shearing implement comprising actuating members arranged in juxtaposition so as to permit lateral movement thereof toward or away one from the other, cutting elements disposed transversely of said members with their edges converging exteriorly on one side of the latter, and pivotal connections at unequal distances apart 55 between the members and said elements, the connections adjacent to said converging edges being at a less distance from each other than the connections remote therefrom.
6. A shearing implement comprising actuating members laterally movable toward or 65 away from each other, and separate cutting elements transversely fulcrumed each at two points and at unequal distances thereon, said elements being adapted to move simultaneously together with their edges converging and arranged to overlap one another exteriorly to one side of both members during 70 their actuation.
7. A shearing implement comprising actuating members operatively disposed one by 75 the side of the other, cutting elements flexibly connected to said members to provide coacting jaws laterally projecting therefrom while in an open position, and automatic means anchored to one of said elements serving to reopen said members subsequently to 80 their being closed.
8. A shearing implement comprising actuating members laterally movable toward or 85 away one from the other, cutting elements independently and transversely connected to said members with their working edges offset to one side thereof, pivots joining said elements to the members at unequal distances apart, and a cam mounted on the 90 pivot located intermediate of the shortest and the longest of said distances, said cam being adapted to contact with one of the elements in various positions and thereby graduate the relative movement between said 95 working edges.
9. A shearing implement comprising actuating members movable from converged to 100 substantially parallel relation on the same side of each other, cutting elements disposed transversely of said members, and pivots connecting said elements with the members, said pivots being located farther apart on one member than on the other, and connecting the two elements at unequal distances 105 with each member.
10. A shearing implement comprising actuating members of different operative lengths adapted to be moved toward or away 110 from each other, cutting elements of unequal lengths transversely joining said members with said elements in fixed pivotal relation, the arrangement being such that the distance of the pivots between the elements is greater on the shorter member than on the longer member, and the spacing of the pivots between the members is less along the shorter element than on the longer element.
- 115 Signed at the borough of Manhattan, in the county of New York and State of New York this 17th day of April, A. D. 1916.
